UNITED STATES PATENT OFFICE.

GEORGE W. PROUTY, OF BOSTON, AND JASPER DERRY, OF MEDFORD, MASSACHUSETTS;
SAID DERRY ASSIGNOR TO ANDREW TERKELSEN, OF BOSTON, MASSACHUSETTS.

FOLDER FOR WRAPPING MACHINES.

Application filed May 9, 1923. Serial No. 637,656.

To all whom it may concern:

Be it known that we, GEORGE W. PROUTY and JASPER DERRY, citizens of the United States, residing at Boston, county of Suffolk, State of Massachusetts, and at Medford, county of Middlesex, State of Massachusetts, respectively, have invented a certain new and useful Improvement in Folders for Wrapping Machines, of which the following is a specification, reference being had therein to the accompanying drawings.

This invention relates to wrapping machines of the general type shown and described in an application for Letters Patent, filed June 21, 1921, by George W. Prouty, Serial No. 479,410, and adapted primarily for wrapping annular objects, such, for example, as automobile tires, coils of wires, etc.

The present invention has for its objects to provide improved means for folding the edge or edges of the strip of paper or other wrapping material applied by the machine, and especially, although not exclusively, to provide means for folding the opposite edges of the strip in opposite directions for the purpose more fully explained in the application for Letters Patent, filed June 10, 1922, by Andrew Terkelsen, Serial No. 567,498.

The foregoing and other objects of the invention, together with means whereby the same may be carried into effect, will best be understood from the following description of one form or embodiment thereof illustrated in the accompanying drawings. It will be understood, however, that the particular construction described and shown has been chosen for illustrative purposes merely, and that the invention, as defined by the claims hereunto appended, may be otherwise practiced without departure from its spirit and scope.

In said drawings:

Fig. 1 is a front elevation of the complete machine.

Fig. 2 is an enlarged front elevation of the paper folder.

Fig. 3 is a plan view thereof.

Figs. 4 and 5 are sections taken substantially on the lines 4, 4 and 5, 5, Figure 2, respectively.

Fig. 6 is a fragmentary detail view of a portion of the wrapped strip.

Referring to Figure 1, the frame of the machine comprises a base 15 and a yoke 16 which is pivotally mounted on a shaft 17 journalled in an upright 18 rising from the base 15. The yoke 16 is provided with guide rollers 19 for an annular shuttle 20 which is rotated by a driving member in the form of a friction disk 21 secured to the shaft 17 and driven through connections (not shown in detail) under the control of a starting treadle 22 from an electric motor 23. The tire or other work W to be wrapped is held by a weighted roller 14 upon work supporting rollers 24 (only one of which is shown in Fig. 1) which are driven through connections generally indicated at 25 from the motor 23, the arrangement being such that the work W will be turned relatively slowly with respect to the speed of rotation of the shuttle 20. Said shuttle is formed with a hinged segment 26 normally closing a gap 75 through which the work W may be inserted, while the yoke 16 may be adjusted about the axis of the shaft 17 to center the shuttle 20 with respect to annular objects of different sizes, said yoke being counterbalanced by a spring 27 and being locked in adjusted position by means of a clamp 28 carried by an upright 29 rising from the base 15.

The wrapping material, preferably in the form of a continuous strip S of paper, is supplied from a roll 30 supported by a reel or spindle 31 carried by the yoke 16. Said paper passes from the roll 30 through the folding device hereinafter more fully described, and designated as a whole in Figure 1 by the numeral 33 and thence over a guide plate 34 to the shuttle 20. Said shuttle 20 comprises an annulus having on one face a circular series of rollers 35 about which the strip S is wrapped when the shuttle is rotated, said strip being fed from the shuttle about a guide roller 36 to the work W. Between the shuttle 20 and the source of supply 30 there is provided a cutting mechanism comprising a knife 37 cooperating with a portion of the guide plate 34 to sever the strip S when a sufficient length thereof has been wound around the shuttle rollers 35 to complete the wrapping of the work W. The knife 37 is automatically actuated, after a predetermined number of rotations of the driving disk 21, by a counting mechanism 38 actuated at each rotation

- of said driving disk by a cam projection 39 thereon, said counting mechanism being manually adjustable in accordance with the size of the articles wrapped.
- 5 From the foregoing the nature, location, and function of the parts referred to will be sufficiently understood for the purposes of the present case. With the exception of those hereinafter described, and in so far 10 as the others enter into combination therewith, as pointed out in the claims, these parts are not involved in the present invention and may be of any suitable construction and arrangement.
- 15 Referring now to Figures 2 to 5, the folding device, to which the present case relates, is preferably carried by a separate plate 40 secured (as by bolts 41, shown in Figure 1) to the yoke 16. Journalled on studs projecting laterally from the plate 40 are guide rollers 42, 43, 44 and 45 over which the strip S passes between a tension device 32 and the guide plate 34. The guide rollers 42 and 43 engage the strip S at opposite sides 20 to guide the same accurately to the first folding device, which is located between the guide rollers 43 and 44. Said folding device comprises a sleeve 46 secured, as by a set screw 47, to a bolt 48 projecting laterally from the plate 40. The sleeve 46 is formed adjacent its inner end with a flange 54 and at its outer end is provided with a collar 52, adjustably secured thereto by a set screw 520, which collar engages and guides the outer 25 edge of the strip S. At the inner edge of said strip, immediately adjacent the flange 54, said sleeve carries a roller 49 mounted for rotation about an axis substantially perpendicular to the axis of the stud 48 and sleeve 46 and to the path of the strip S, upon a stud or pin 50 projecting from said sleeve. The inner end of the roller 49 is of compound curvature, being preferably of substantially pseudo-spherical shape, so that, as 30 the strip S is drawn past the same, the adjacent edge of said strip will be turned to form a fold a which is subsequently flattened down upon the surface of the strip by the passage of the latter about the guide roller 44.
- 35 The flange 54 is suitably cut away to receive the enlarged inner end of the roller 49, and the sleeve 46 is also cut away immediately adjacent said roller 49 to form a recess 51 which receives the folded edge a of the strip.
- 40 The sleeve 46 is also provided adjacent the recess 51 with a spaced, parallel stud 53 projecting from the flange 54 and between which and the body of the sleeve the strip passes. The second folding device, which is located 45 between the guide rollers 44 and 45, is similar to that just described and comprises a sleeve 55 secured by a set screw 56 to a stud 57 projecting from the plate 40, said sleeve having a flange 58 adjacent its inner end and a roller 59 mounted on a pin 60 to rotate 50 about an axis substantially perpendicular to the axis of the sleeve 55 and stud 57 and to the path of the strip S, the roller 59 being pseudo-spherical at its inner end, adjacent which the sleeve 55 is formed with a recess 61, and provided with a guide pin 62 projecting from the flange 58. In this instance, however, the roller 59 is carried by the outer end of the sleeve 55, so as to engage the opposite edge of the strip S from that engaged 55 by the roller 49 and turn said opposite edge so as to form a fold b which is flattened down by the subsequent passage of the strip about the guide roller 45.
- 55 It will be observed that the sleeves 46 and 55 engage the strip S at opposite sides, so that the rollers 49 and 59 operate to turn the opposite edges of the strip in opposite directions, the fold a being outward, with respect to the subsequently wrapped strip, and the 60 fold b being inward. The folds a and b of adjacent strips are therefore opposed and tend to interlock, as indicated in Figure 6, thereby preventing the separation of the strips and the exposure of the article 65 wrapped.
- 65 It will be observed that by releasing the set screws 520 and 56 the collar 52 and sleeve 55 may be longitudinally adjusted laterally of the strip S, thereby adapting the 70 folding device to strips of any width.
- 75 It will be understood that, while the axes of the guide rollers 42, 43, 44, and 45 and of the sleeves 46 and 55 of the folding devices are all parallel to one another, and preferably perpendicular to the plate 40, the precise arrangement of these parts on said plate may be varied in accordance with the requirements of the particular machine, it being necessary only that the sleeves 46 and 55 80 engage the strip at opposite sides, and that the strip be accurately guided to the sleeve 46, from said sleeve 46 to the sleeve 55, and from the latter sleeve, in such a manner as to cause the proper engagement of the edges 85 of said strip with the rollers 49 and 59 and the subsequent flattening of the folds resulting from the turning of the edges of the strip by said rollers. To the latter end a light tension is preferably applied to the 90 strip, this, in the present instance, being accomplished by means of a leaf spring 65 secured to the sleeve 46 and engaging the strip as it passes over the guide roller 43.
- 95 Certain features shown and referred to herein are covered by claims of other applications for Letters Patent, as follows:
- 100 As to the machine as a whole, application Serial No. 479,410, above referred to;
- 105 As to the driving mechanism, application Serial No. 637,655, filed May 9, 1923, by ourselves and Philip O. Tengberg;
- 110 As to the means for supporting and adjusting the shuttle-carrying yoke, Serial No. 637,657, filed May 9, 1923, by ourselves;

As to the shuttle in combination with certain cooperating parts, Serial No. 637,618, filed May 9, 1923, by Jasper Derry; and

As to the work supporting rollers and associated parts, Serial No. 637,658, filed May 9, 1923, by George W. Prouty.

Having thus described our invention, we claim—

1. In a wrapping machine comprising a work support, an annular shuttle through which the work is adapted to be moved, means for moving said shuttle about its center, and means removed from the shuttle for supplying wrapping material in a continuous strip; a device between said supplying means and shuttle for folding the edge of said strip of material.

2. In a machine for wrapping objects with a spirally wound strip of material and comprising a frame, a work support thereon and an annular shuttle; a folding device located on said frame for folding the edge of said strip.

3. In a machine for wrapping objects with a spirally wound strip of material and comprising a frame, a work support thereon, and an annular shuttle; a folding device located on said frame and comprising means for folding both edges of said strip during the passage thereof of said shuttle.

4. In a wrapping machine comprising a work support, an annular shuttle through which the work is adapted to be moved, and means for feeding a strip of wrapping material from the shuttle around said work, a plurality of rollers disposed with their axes substantially perpendicular to the path of said strip of material and adapted to fold over the edges of the material prior to winding thereof about the work.

5. In a machine for wrapping objects with a spirally wound strip of material and comprising a frame, a work support thereon, an annular shuttle, and means for supplying said material to said shuttle; a roller mounted on said frame and disposed with its axis substantially perpendicular to the path of said strip for folding the edge thereof.

6. In a machine for wrapping objects with a spirally wound strip of material, a folder comprising a roller having a substantially pseudo-spherical portion adapted to turn the edge of said strip.

7. In a machine for wrapping objects with a spirally wound strip of material, a folder comprising a stud over which said strip passes and a roller carried by said stud at the edge of the strip with its axis substantially perpendicular to the axis of said stud.

8. In a machine for wrapping objects with a spirally wound strip of material and comprising a frame, a work support, an annular shuttle, and means for supplying said material to said shuttle; a folder on said frame between said shuttle and said supplying means, and means whereby said folder may be adjusted transversely of said strip.

9. In a machine for wrapping objects with a spirally wound strip, a folding device comprising members arranged to engage said strip at opposite sides and provided with means for turning the opposite edges thereof in opposite directions, and devices for guiding said strip to one of said members, between said members, and from the other of said members.

10. In a machine for wrapping objects with a spirally wound strip, a folding device comprising a member over which said strip is guided, said member having a recess adjacent the edge of said strip and a roller extending laterally therefrom adjacent said recess, said roller having a portion adapted to turn the edge of said strip into said recess.

11. In a machine for wrapping objects with a spirally wound strip, a folding device comprising a member having a spaced parallel stud between which and a portion of the surface of said member said strip is guided, said member having a recess adjacent the edge of said strip and a roller extending laterally therefrom adjacent said recess, said roller having a portion adapted to turn the edge of said strip into said recess.

12. In a machine for wrapping objects with a spirally wound strip, a folding device for turning the edge of said strip, means for guiding said strip to said folding device, and a spring for pressing said strip against said guiding means to apply tension thereto as it is folded.

In testimony whereof we affix our signatures.

GEORGE W. PROUTY.
JASPER DERRY.
